DESIGN FOR A SOUND TRANSLATING MACHINE

Raymond Spilman, Yonkers, N. Y., assignor to
The Gray Manufacturing Company, a corpora-
tion of Connecticut

Application September 12, 1946, Serial No. 133,269

Term of patent 14 years

(Cl. D26—14)

To all whom it may concern:

Be it known that I, Raymond Spilman, a citizen of the United States, residing at Yonkers, in the county of Westchester, State of New York, have invented a new, original, and ornamental Design for a Sound Translating Machine, of which the following is a specification, reference being had to the accompanying drawing, forming part thereof.

Fig. 1 is a perspective view from a front corner,

showing the front, top and one side of a sound translating machine, showing my new design; and

Fig. 2 is a perspective view from a rear corner showing the rear, top and other side of the sound translating machine.

I claim:

The ornamental design for a sound translating machine, as shown.

RAYMOND SPILMAN.
